UNITED STATES PATENT OFFICE.

EDWARD ALPHONSE FARISH, OF AUTEUIL, FRANCE.

POLISH APPLYING AND RUBBING IMPLEMENT.

Application filed February 27, 1924, Serial No. 695,404, and in France March 1, 1923.

This invention relates primarily to a self contained brush for scraping, brushing, applying polish and shining boots and shoes.

According to this invention the polish is supplied to the brush from a tube carried in the handle of the brush and is forced from the tube into the bristles of the brush by some suitable arrangement. The brush is divided into several parts comprising the 10 cleaning brush, the brush for applying the polish and the polishing brush, so arranged as not to interfere with one another. The brush is preferably supplied with a scraper.

To force the polish from the tube a special 15 key may be used which can serve for several successive tubes of polish. Such key may consist of a rod with a slot in it, one end of which is supplied with means for turning it and the other end with a flat removable 20 head. When the key is turned the rod rolls along the top of the brush at the same time winding up the tube and forcing out the 25 polish.

In place of a slotted key in which the thin 30 end of the tube is enclosed a roller may be used, carried on a spindle having toothed wheels that run along a rack. This roller is also provided with means for turning it and so squeezing and flattening out the 35 tube as it is turned.

The tube of polish used with this brush has preferably a neck curved so as to penetrate into the bristles of the polishing brush; this neck may be removable, so that it can 40 be fitted to another tube when the polish has run out.

An arrangement may be provided for securing the tube in position, consisting of a plate sliding transversely to the brush and having in it a slot, one end of which is sufficiently large for the neck of the tube to pass 45 through it so that when the plate is in its displaced position, the enlarged portion of the slot corresponds with the passage in the brush and the tube may be removed.

The wood mountings are preferably independent of one another, and separate, so as to facilitate their replacement. These parts of the mounting are carried in a metal plate 50 forming a frame whose edges are suitably bent to engage in slots or grooves in the sides of the mounting.

The central part of the mounting may, instead of the polishing brush, consist of a

pad covered with some suitable polishing material (plush, wool, etc.) which can easily be replaced.

The use of this brush saves a great deal of time and labour in cleaning and polishing shoes, and also prevents the fingers from becoming soiled and the trouble of having a number of brushes and a separate tin of boot polish. In this case the polish is applied to the polishing brush by the mere movement of the key and the tube of polish 65 when finished may be replaced by another one.

The invention is illustrated in the accompanying drawings in which Figure 1 is a side elevation of a brush, with the cover open. Figure 2 is a plan of Figure 1. Figures 3 and 4 are similar views with the cover closed. Figures 5 and 6 are detail views of the tube containing polish. Figure 7 is a side elevation of a modification with the cover raised. Figure 8 is a plan view with the cover removed. Figures 9 and 10 are respectively sections on the lines 1-1 and 2-2 of Figure 7, the tube containing the 70 polish being omitted in Figure 10. Figure 11 shows a modification of the central part of the mounting. Figures 12 and 13 show alternative forms of the key having a roller for compressing the tube containing the 75 polish.

The implement comprises a plurality of mountings including a polishing brush *b*' on a wood back *a'*, a dust removing brush *b*² and a polish applying brush *b*³, respectively mounted on backs *a*², *a*³, carried by the 80 back *a'*.

Backs *a'*, *a*², and *a*³ are secured to and supported upon a metal plate or support *c* terminating at one end in a projection *c*' which acts as a scraper for removing mud. To the other end of plate *c* a cover *e* is hingedly secured as indicated at *d* which cover encloses the tube containing polish. Cover *e* is preferably given a rounded shape to form a handle and is maintained in its closed position by means of a plate *g* which may be turned on its pivot *h* so that its edge *g*' comes over a projection *e*' on cover *e*. To enable a better grip to be obtained of the cover *e*, the back *a'* thereof is provided on its sides with grooves *f*.

The element *i* is a tube containing polish, arranged within the cover *e* with its neck *i*'

(the cap having previously been removed) in a passage k formed in the back a^3 which leads to the bristles of brush b^3 . After the neck i' of tube i has been placed in passage k the tube i is bent back flat on to the back a' and the thin end of the tube i is inserted in the slot of a key l . The cover e is then secured in position and the brush is ready for use; polish is expelled from the tube by turning the key l by the aid of its projecting head l' .

To clean a shoe it is first scraped with scraper c' , then brushed with the brush b^2 , key l is given a turn or two so as to wind up part of the tube on to the key and so force polish through passage k into the hairs of brush b^3 . The shoe is then rubbed with brush b^3 to apply the polish and thereafter polished with brush b^2 . The brush is now ready to clean another shoe, the key l being given a further turn when it is necessary to supply brush b^3 with more polish. When tube i is empty it is replaced by a fresh tube. Tube i preferably takes the form either as illustrated in Figure 5 or Figure 6. In Figure 5 the tube is provided with a removable curved neck m which, as illustrated, screws on to the neck of the tube, but it may be otherwise secured thereto. In Figure 6 the curved neck m' is a fixture on tube i and may terminate in a screw cap.

In Figures 7 to 10, A' , A^2 , A^3 indicate in the first form of the invention the backs of the three brushes formed as separate mountings but in this modifications they are removably mounted on the metal plate or support c . The edges 1 of the plates C are bent so as to engage in recesses 2, as in Figure 9, or in grooves 3, as in Figure 10, formed in the sides of the brush backs A' , A^2 , A^3 . The back A' may, as shown in Figure 11, be provided with a pad in place of a brush B' ; the pad may be formed of a cover 4 of linen, plush or other suitable material, a piece of wood 5 and a layer of felt between cover 4 and the wood 5.

The wood 5 may be secured to the back a' by means of a suitable screw. The cover 4 is held in position by a spring wire clip 6, engaging a groove 7 in the wood 5. Two pins or nails 8 pass into holes in the wood 5 and hold it in position. The hollow grip or cover E is completely removable. One of its ends 9 engages a slot 9' in plate C while its other end 9'' is secured to the other end of the plate by a small spring catch 10' which rides over a projection 10 on the end of the back A^3 .

An alternative form of winding key consists, as is shown in Figure 8, of a split rod provided at one end with a screw head 11 and at the other end with a head 12 in which is a turning loop 13. This key operates as

before and may be used for successive tubes of polish.

To withdraw the key, head 11 is unscrewed and the rod withdrawn from the tube without it being necessary to unwind it. The heads 11 and 12 serve, moreover, as guides and prevent any displacement of the key.

In place of a key a roller 14 (Figures 12 and 13) may squeeze the tube I . The spindle of roller 14 has fast on it two toothed wheels 15 which engage in racks 16 projecting through slots in the plate E . The spindle portion 17 of roller 14 engages in slots 18 and 18' in the side of the cover e and is rotated by turning loop 13. The neck I' of tube I is held in position on the back A^3 by a slide 21 operated by a handle 22; slide 21 has a hole 23 through which the neck I' can pass freely, and a narrower slot 24 leading into hole 23; when the slide is in its holding position, the edges of slot 24 engage grooves I^2 formed in the neck of the tube, so holding it firmly. Brush B^3 is free from bristles where the neck I' is led out so as not to impede the expulsion of polish from tube I .

The brush herein described with reference to cleaning boots and shoes is not confined to this usage but is applicable to cleaning other articles in which a polish is applied and treated frictionally.

What I claim is:—

1. In an implement of the character described, the combination with a flanged supporting plate, of a mounting provided with a rubbing surface and having means for engagement with the flanges on said plate for retaining said mounting thereon, a collapsible tube for containing polish, means for retaining said tube on said plate, said mounting having a hole therein leading to the rubbing surface thereof for receiving a portion of said tube, and means for ejecting polish from said tube.

2. In a polishing implement provided with a rubbing surface, a collapsible tube containing polish and provided with an outlet pipe, said outlet pipe having a grooved portion thereon, means for retaining said tube on said implement, said implement having a hole therein leading to the rubbing surface thereof for receiving the outlet pipe of said collapsible tube, means for ejecting polish from said tube, a slide provided with a hole allowing the easy passage of said pipe therethrough and with a narrower slot communicating with said hole adapted to engage the grooved portion of said pipe and keep it in position.

In testimony that I claim the foregoing as my invention I have signed my name this 9th day of February, 1924.

EDWARD ALPHONSE FARISH.
